RICHARD CLANTON, OF NORTH HOLLYWOOD, CALIFORNIA, ASSIGNOR OF ONE-HALF TO
PAUL KRAMER, OF NORTH HOLLYWOOD, CALIFORNIA

MECHANICAL SAND WASHER

Application filed June 6, 1930. Serial No. 459,537.

This invention relates to mechanical sand washers or machines designed to wash foreign substance from sand, and prepare it for marketing.

5 In practice, where large quantities of clean sand are required, it is customary to wash the sand by means of a mechanical arrangement, whereby the sand is worked through a bath of water, is finally delivered from the water 10 as a clean sand product. The type of machines used for this purpose consists of an inclined trough arrangement, leading from the water bath, with a plurality of drag blades arranged within the trough to reciprocate and draw the sand out of the water 15 and up the inclined trough. The objection to this arrangement is the fact that as the drag blades pull the sand up the incline, the sand, after leaving the water, is still so thoroughly saturated with water that it is in a 20 more or less plastic condition, and as the blades leave the sand to return for another load, the piles of sand will flow or recede to a great extent downwardly to its original position, and, as a result, the efficiency of the 25 machine is greatly reduced.

A further objection is raised with respect to the water content of the final product. With the present equipment, the sand delivered at the upper end of the inclined trough contains a high percentage of water. In some cases this wet sand is delivered directly into trucks which convey it to the job. However, since the sand still contains so much water, it drains from the truck and drips onto the ground. This prevents the truck from going onto highways or streets immediately, since, in most cases, traffic regulations provide against driving dripping vehicles over public roadways. The result is, the truck must stand idle with the load until the dripping has ceased, thus causing a loss of time and adding to the cost of transportation. In other cases, the sand is deposited from the upper end of the inclined trough onto a conveyor belt, and then conveyed to storage bins where it is allowed to drain. The plastic condition of the saturated sand again raises a serious objection, in that excessively broad belts must be used in order to

accommodate the spreading of the sand, and even then it will run off the edge of the belt and into the bearings for the rollers. Furthermore, in arrangements of this type, provision must be made to handle the drainage 55 water after the sand is stored in order that trucks may approach the bins for a load. Perceiving that these objections could be substantially eliminated, and the output of the machine increased, I conceived the idea of 60 draining the sand before it left the machine by providing water drains in the drag blades which would permit the water to compress from the sand and pass through the blades on the upstroke. This operates effectively 65 and efficiently to produce a drier sand product on each successive stroke, since the sand, while being forced up the incline, is in an ideal state for dewatering. This result is a 70 final product of comparatively dry sand. Accordingly, it becomes an object of this invention to provide drag blades in mechanical sand washers of the character described with 75 perforations either in the nature of holes or screening in the body of the blade to drain water during the operation of dragging the sand up the inclined trough.

A noteworthy feature of my invention consists in countersinking the holes on the side of the blade opposite the sand. This results 80 in producing openings through the blades that are free from clogging, and remain substantially self-cleaning. Accordingly, it becomes a more specific object of this invention to provide drag blades having countersunk 85 holes therethrough.

Other objects and advantages will become apparent as the description proceeds in conjunction with the drawing in which—

Fig. 1 is a sectional view showing my invention embodied in combination with a conventional mechanical sand washer;

Fig. 2 is an enlarged fragmentary view of the drag blades showing more clearly my invention;

Fig. 3 is a section taken on line 3—3 of Fig. 2; and

Fig. 4 shows another form which my invention may take.

Referring to the drawing, and particularly

to Fig. 1, I have illustrated a conventional sand washing machine. Such a machine usually comprises a water tank A for washing the sand, an inclined trough B joined to the water tank in a manner to receive the sand from the water tank and a drag blade arrangement generally designated C. The drag blade arrangement is mounted upon a superstructure 11 by means of links 12 and bell cranks 13. 5 Means is provided for reciprocating the drag blade arrangement C within the trough B to drag sand from the water tank A up the inclined trough, such means consisting of a double eccentric shown at 14, and having connected therewith a pair of connecting rods 15 and 16. The connecting rod 15 is arranged to lift the drag blades on the return stroke by means of the bell cranks 13 and the links 12, and the rod 16 is arranged to reciprocate the 10 drag blade arrangement, the two movements being so synchronized that the drag blades will operate to draw sand up the incline and will return in an elevated position for another load of sand. The sand, consequently, 15 is left in small piles on the bottom of the inclined trough. When the sand is worked up the inclined trough B to the point 17, it is dropped either into a truck, a conveyor system, or a storage bin. 20 My invention, as before stated, deals with a means for dewatering the sand as it is propelled up the inclined trough. Such a means I have illustrated in Figs. 3 and 4. More specifically describing this embodiment of my invention, it is observed that the drag blade arrangement is equipped with a pair of channel irons, shown at 18 and 19. Attached to the members 18 and 19 are a plurality of drag blades designated 20. The means of attaching the blades 20 to the channel irons 18 and 19 consists of a member 21, which, in this instance, is a piece of angle iron bent at right angles to form legs 22 and 23. The leg 22 is attached to the lower side of the channel 25 18 by means of a bolt 24, and the leg 23 is utilized for mounting the blade 20 by means of bolts 26. A brace member 26 extends from the lower bolt 25 to the lower edge of the channel iron 18 and is attached thereto by means of a bolt 27. It is to be understood that the same structure is utilized in connection with the channel iron 19. This structure will be recognized as providing a rigid mounting for the blades 20. As before stated, the purpose of this invention is to provide in the blades 20 a means of dewatering the sand as it is dragged up the incline. The preferred means is shown in Figs. 2 and 3, and consists of holes 28 30 through the body of the plate. 35

In Fig. 4, I have shown another form which consists of incorporating a screen 29 for the main body of the blade.

In practice, I have found that holes of uniform bore have a tendency to clog and reduce the efficiency of my invention. Accordingly,

I prefer to countersink the holes on the side opposite the sand. This results in providing a substantially self-cleaning aperture.

In operation, as the drag blades 20 draw the sand up the inclined trough B, the sand accumulates in front of the blade somewhat as shown at 30. It is understood that as the sand leaves the tank A, it is thoroughly saturated with water, and that unless the water is given an opportunity to drain out of the sand, the sand will be in such a plastic condition that as the blade leaves the sand in a series of piles in the trough and returns on its downward stroke, the sand, due to gravity, will flow downwardly with the blade and the efficiency of the machine will be greatly reduced. With my invention, a large percentage of the water in the sand in front of the blade is allowed to compress out of the sand and pass through the holes 28, whereupon it flows downwardly over the back of the blade and will flow down the trough under the piles of sand and back into the tank A. The result is that each pile of sand is more quickly dewatered than if the water were forced to drain out of the bottom of the sand piles. The final product is delivered over the end 17 of the trough B in a comparatively dry state. Not only is this benefit achieved, but also is each pile of sand successively dewatered and left in a drier condition, whereby it will better maintain its position as the blade leaves it for the return stroke. This clearly increases the efficiency of the machine, since the blade on the upstroke is enabled to pick up a greater load of sand. 40

The foregoing advantages will be recognized as a result of my invention.

Although I have shown drag blades equipped with holes and with screens, nevertheless, I am aware that other expedients, such as irregular openings, slots, etc., will perform to obtain the same results. Therefore, it is to be understood that this disclosure is intended to include drag blades of the nature described having openings therethrough adapted to pass water. 45

I claim as my invention:

In a mechanical sand washer having an inclined trough with drag blades adapted to drag sand up the trough: means associated with said blades for dewatering the sand as it is forced up the inclined trough, said means embodying holes through said blades adapted to pass water and restrain sand, said holes being countersunk on the side opposite the sand. 50

In testimony whereof, I have hereunto set my hand at Los Angeles, California, this 29th day of May, 1930.

RICHARD CLANTON.
